UNITED STATES PATENT OFFICE.

JOHN C. GRAHAM, OF PHILADELPHIA, PENNSYLVANIA.

DESIGN FOR GIMP.

SPECIFICATION forming part of Design No. 12,086, dated January 4, 1881.

Application filed December 10, 1880. Term of patent 7 years.

To all whom it may concern:

Be it known that I, JOHN C. GRAHAM, of the city and county of Philadelphia, in the State of Pennsylvania, have invented and produced a new and original Design for Gimp, of which design the following is a specification.

The accompanying drawing is a face view of a pattern of gimp embodying and illustrating my design, which consists in a gimp having heavy or coarse weft-threads *a* and a central band or stripe, *b*, formed by a series of lighter warp-threads extending along the gimp for the major portion of its width alternately over and under the weft threads *a*, and so on throughout the length of the piece. The central band, *b*, is divided at regular intervals into separate blocks or sections by another series of light warp-threads, forming narrow transverse bars *c*, each interposed between two of the sections of the band *b*, and also forming, by passing over and under the warp-threads, a zigzag line of checkers or small

squares, *d*, on each side of the central band. For further embellishment a narrow longitudinal stripe, *e*, may be added adjacent to each side of the gimp, if desired.

In order that the design may be clearly developed, the threads forming the transverse bars *c* and the zigzag lines of checkers *d* should be of different color from those forming the band *b* and the background of weft threads *a* of different color from the band, bars, and checkers.

I claim—

A design for gimp consisting of a background of weft-threads ornamented by a central longitudinal band or stripe divided into blocks or sections by narrow transverse bars, and a zigzag line of checkers or small squares on each side of the central band or stripe, substantially as set forth.

J. C. GRAHAM.
